COMBINED DISPLAY AND DISPENSING STAND OR THE LIKE

Forrest C. Brady, 301 51st Place, Western Springs, Ill.

Filed Oct. 14, 1963, Ser. No. 76,961

Term of patent 14 years

(Cl. D80—10)

FIG. 1

FIG. 3

FIG. 1 is a front perspective view of a combined display and dispensing stand or the like embodying the new design;

FIG. 2 is an elevation view taken from the right side thereof, the left side being essentially the same as the side shown with the small holding member removed; and

FIG. 3 is a rear elevational view of the top portion thereof, the bottom being omitted for convenience of illustration.

I claim:

The ornamental design for a combined display and dispensing stand or the like, as shown and described.
